CLAIM

The ornamental design for shoulder bags, as shown and described.

DESCRIPTION

FIG. 1 is a perspective view of shoulder bags showing my new design with the bags connected together and to the shoulder strap;

FIG. 2 is a top plan view of the shoulder bags shown in FIG. 1.

FIG. 3 is a bottom plan view of the shoulder bags shown in FIG. 1.

FIG. 4 is a front elevational view of the shoulder bags shown in FIG. 1.

FIG. 5 is a rear elevational view of the shoulder bags shown in FIG. 1.

FIG. 6 is a left end elevational view of the shoulder bags shown in FIG. 1.

FIG. 7 is a right end elevational view of the shoulder bags shown in FIG. 1.

FIG. 8 is a perspective view of the shoulder bags with the intermediary web expanded and the shoulder strap and auxilliary strap connected to the lower 'D' rings on the right and left ends;

FIG. 9 is a top plan view of the shoulder bags shown in FIG. 8.

FIG. 10 is a bottom plan view of the shoulder bags shown in FIG. 8.

FIG. 11 is a right end elevational view of the shoulder bags shown in FIG. 8.

FIG. 12 is a left end elevational view of the shoulder bags shown in FIG. 8.

FIG. 13 is a front elevational view of the shoulder bags shown in FIG. 8.

FIG. 14 is a rear elevational view of the shoulder bags shown in FIG. 8.
